UNITED STATES PATENT OFFICE.

CARL HEROLD AND RICHARD RICHARDS, OF BRÜNN, AUSTRIA-HUNGARY.

CIRCULAR LOOM.

SPECIFICATION forming part of Letters Patent No. 636,800, dated November 14, 1899.

Application filed June 7, 1899. Serial No. 719,731. (No model.)

To all whom it may concern:

Be it known that we, CARL HEROLD and RICHARD RICHARDS, manufacturers, residing at 44 Teile, in the city of Brünn, Empire of Austria - Hungary, have invented new and useful Improvements in Circular Looms; and we do hereby declare the following to be a full, clear, and exact description of the same.

This invention relates to improvements in the circular looms described in the application of Herold and Herold, filed June 25, 1898, Serial No. 684,502, patented July 4, 1899, No. 628,093, and refers to (a) the mechanism for forming the shed and (b) the mechanism for beating up the weft (shuttle-thread) in the woven fabric.

The circular loom provided with these improvements is illustrated in the accompanying drawings, as follows:

Figure 1 is a vertical section and elevation of the loom; Fig. 2, a vertical section and elevation of a part of the loom on an enlarged scale to illustrate more clearly the details; Fig. 3, a sectional elevation of a modification of the mechanism for beating up the weft; Fig. 4, a plan of the parts shown in Fig. 2; Fig. 5, a side elevation, partly in section, of the driving mechanism; Fig. 6, a side elevation of portion of the rotating cam for actuating the beaters; Fig. 7, a side view of outer end of heald-carrier on an enlarged scale and partly in section; Fig. 8, an end view of the same; Fig. 9, a side view, partly in section, of the inner end of the heald-carrier; Fig. 10, a plan view of the same; Fig. 11, a side view, partly in section, showing roller in section; and Fig. 12, a side view of the shuttle.

Motion is imparted to the vertical shaft a from the horizontal shaft a' by means of the beveled wheels a^2 a^3 . One end of the vertical shaft a is supported in the footstep b and the other end in the collar b' , which latter is let into the pedestal or bracket b^2 . The bracket b^2 is firmly screwed to the center cross rail or beam b^3 , which connects the two beams b^4 of the frame. The pedestals b^5 of the shaft a' are attached to the same frame. The remainder of the frame consists of two side uprights c , which are connected at the top by two cross-rails. Each of the latter carries a head-piece, by which the cloth-rollers r are supported.

The shuttle race-rings m m' are formed each of one piece, and the actuation of the shuttles and their motions are in other respects effected by horizontally-placed electromagnets n with radial poles. These electromagnets receive the current from some source of current through the intermediary of a sliding contact located on but insulated from the shaft a . The contact consists of a collar m^5 , made of insulating material—such as wood, hard rubber, ebonite, or the like—upon which two brass rings m^6 m^7 are fixed. A brass spring m^4 rubs against each of these rings. The wires m^0 m^2 , leading from the source of current, are connected with the supports m^3 of these contact-springs. From the rings m^6 m^7 conducting-wires m^8 m^9 lead to the successive magnet-coils n . The boss o , fixed to the shaft by nuts o' o' , which carries the electromagnets, is in one piece with the lowest of the cams or eccentrics d for forming the shed.

The arrangement of the eccentrics or cams d for forming the shed is the same as that described in Patent No. 628,093, the annular eccentrics or cams d being placed one above the other and fastened together by bolts or screws d^2 passing through them. The wire healds e^4 have their outer ends drawn out to engage with or fit over the curved pieces or rods f' . (For these see Fig. 8.) To each of the latter there is a ring or eye r' riveted, Fig. 8, which can be placed upon or over the outer end of the strong wire e^5 , the latter having on it a screw-thread, so that the ring can be fixed by the two nuts e^6 , Fig. 7. As may be seen from the drawings, the wire healds e^4 are situated above the wire rods e^5 ; but they may equally well be placed underneath. This wire e^5 at its inner end is screwed into the head e^7 , and the head e^7 is by means of a stud e^8 connected to the plate e^9 . The stud is preferably fixed to the head e^7 and turns in the plate e^9 , Figs. 9 and 10. The plate e^9 carries underneath at both ends rollers e' , which rotate on the studs e^2 . These rollers run in the grooves e of the eccentric d for forming the shed, Figs. 2 and 4, and by their passing from the outer to the inner part of the groove, or the contrary way, impart a radial to-and-fro movement to the wires e^5 and also to the wire healds e^4 , both of which are guided by the holes g^2 of the casing g^3 , by which means the shed is pro-

duced. The nut e^8 , forming the top of the bolt e^2 , prevents the rollers e' and the head e^7 from jumping out of the groove e , as they almost touch the eccentric d or plate d' above them. By the plate e^9 and head e^7 , Fig. 9, being made to turn about each other it is made possible that the wire e^5 , which is screwed into the latter, remains radial during all the movements, more particularly while passing from the inner to the outer part of the groove e of the eccentric d , or vice versa, so that any jamming or bending of the wire healds is avoided. The wire here referred to replaces the intermediate pieces e^3 of Patent No. 628,093, and this arrangement has the advantage over the older one that the wire healds e^4 , attached to the curved pieces f' , are accessible from the outside.

The arrangement of two rollers e' on both sides of the wire e^5 is for the purpose of preventing the rollers from jamming in the grooves e of the eccentric.

The shuttle s is shown in side elevation in Fig. 12 and in end elevation in Fig. 2. It has at each end an upright roller s' , which runs in contact with the race-rings $m m'$. Projecting from its outer side are two short studs, on which are mounted wheels s^2 , resting and running upon the reeds h^5 . The rollers s' lie in the same radial lines as the cores n of the electromagnets.

The beating up of the weft-thread which has been carried through by the shuttle is not now effected by the reed-segments of Patent No. 628,093, but by beaters which are placed near to the apex of the shed, which have the advantage, compared with the movement of the segments in said application, that they have a much shorter distance to traverse in moving from their position of rest into the dotted-line position for beating up the weft. In order to make this arrangement practicable, the thread issuing from the shuttle s must be brought near to the apex of the shed, and for this purpose there projects from the upper side of the shuttle a fixed wire r^2 , Figs. 1, 2, and 12, which reaches nearly to the apex of the shed and has an eye r for the thread, through which the weft as it comes off the cop or spool is led.

The new arrangement for beating up the weft consists of a grooved ring h^3 , revolving with the shaft a , the groove k being formed with several sharp bends, into which project the arms h^9 of the beaters h , which swing or oscillate on a closed ring h^8 . The ring h^3 is supported by carriers c' , fixed to the beam-ring C , and an annular weight or ring c^2 is laid upon the beaters h , which may, if desired, be fixed against an elastic packing c^3 on the beam-ring C . This weight serves to hold the beaters down on the ring h^3 . For the purpose of obtaining a surer guide for the beaters h they are guided by vertical slits c^4 in the cylinders c^5 . As soon as the shuttles s , carried around by the electromagnets n , have paid off a portion of the thread the beaters by reason

of the arm h^9 passing into the sharp bend k^4 , Figs. 1, 2, and 6, strike the paid-off weft underneath, push it up from below, and finally 70 attain the dotted-line position, Fig. 2, where they press the weft to the finished cloth and then return to their previous position. It should be noted that the number of sharp bends k^4 in the cam h^3 corresponds with the 75 number of shuttles s .

In the modification illustrated in Fig. 3 for beating up the weft the form of the beaters h is such that in either the full-line or dotted-line position they are constantly between the 80 threads of both the inner and the outer part of the shed, by which the possibility of the beaters failing to pass between the threads is avoided. To attain this object, the beaters h are prolonged into curved ends h^6 , so that in 85 the full-line position these curved ends play between two particular threads or groups of threads of the outer portion of the shed and only leave these when the particular point h^7 of the same beater which has to beat up the 90 weft has entered between the two threads or groups of threads. In this arrangement the ring h^3 is supported in the holes of the carriers c' , which are fixed on the inner side of the shuttle race-ring m' .

In operation the circular loom works as follows: The warp-threads pass from the warp-beams t over the rail or beam t' and cross-rings t^2 to the healds e^4 and are then drawn through the stationary reed h^5 . The shuttles s , which are brought into the shed thus formed, are carried around in a circle by the rotating electromagnets n and introduce the weft-threads. When a given length of the weft-thread has been carried into the shed and the 105 magnets, with the shuttles, have passed, the arm h^9 enters the inwardly-inclined bend k^4 of the groove or path k of the revolving cam h^3 , whereby the lever h is moved about its central pivot h^8 and beats the weft upward 110 into the cloth. As soon as the weft is beaten up the levers h resume their original position, owing to the arm h^9 reentering the concentric part of the groove or path k of the cam h^3 . The heddle-cams d open the shed before each 115 shuttle and change it after the shuttle has passed, this movement being effected by the corresponding curves in the grooves e .

Having thus described our invention, what we claim, and desire to secure by Letters Patent, is—

1. In a circular loom, mechanism for forming the shed, comprising a stationary framing provided with holes, radial wires sliding in said holes and projecting beyond the framing, 125 rods secured to the outer ends of said wires, healds attached to the rods and running in radially through holes in the framing, and rotatable cams engaging with the inner ends of the wires.

2. In a circular loom, mechanism for forming the shed, comprising a stationary framing provided with guide-holes, radial wires sliding in said holes, a ring secured to the

outer end of each wire, a rod attached to the ring transverse to the wire, radial healds having their outer ends attached to the rod and their inner ends passing freely through the 5 guide-holes, and rotatable superposed cams engaging with the inner ends of the wires, and between which the ends of the healds can enter.

3. In a circular loom, the combination with 10 rotatable cams having eccentric grooves, of radial heald-carrying wires, having at their inner ends pivoted plates, and a roller at each end of said plates engaging with said grooves.

4. In a circular loom, the combination with 15 a shuttle having an upright arm for guiding the thread, of pivoted beaters placed above the same near the apex of the shed, a rotatable ring having a cam-groove engaging with the inner ends of said beaters, and a slotted 20 casing for guiding the beaters.

5. In a circular loom, the combination with

stationary casings having upright slots, of a ring supported between the casings, radial beaters pivoted on said ring and projecting at each end through said slots, a rotatable 25 cam-ring engaging with the inner ends of said beaters, and an annular weight resting on said beaters above the pivot-ring.

6. In a circular loom, a weft-beater having an arm h^3 provided with a curved extension 30 h^6 and a point h^7 , whereby some portion of the beater will always be between both threads of the shed.

In testimony whereof we have signed this specification in the presence of two subscr- 35 ing witnesses.

CARL HEROLD.
RICHARD RICHARDS.
